UNITED STATES PATENT OFFICE.

ANNA M. SUBBERG, OF CHICAGO, ILLINOIS.

SHOE-RACK.

1,030,940.

Specification of Letters Patent.

Patented July 2, 1912.

Application filed January 16, 1911. Serial No. 602,949.

To all whom it may concern:

Be it known that I, ANNA M. SUBBERG, a citizen of the United States, and a resident of the city of Chicago, county of Cook, and 5 State of Illinois, have invented certain new and useful Improvements in Shoe-Racks, of which the following is a specification.

My invention relates to improvements in shoe racks designed for holding shoes, slippers, rubbers and other like footwear which 10 can be readily fastened to a suitable support, such as the wall of a room or door, at a suitable height to be readily accessible.

The object of my invention is to provide 15 a shoe rack, as stated, and provide means in connection therewith for collecting the dirt and drippings from wet rubbers or shoes, and thereby avoid soiling the floor.

A further object of my invention is to 20 provide an improved rack of simple construction which shall be adapted for use in private families, clubs, and schools, and similar places where persons are in the habit of removing their overshoes.

25 Other objects will appear hereinafter.

With these objects in view my invention 30 consists in the novel construction and arrangements of parts all as will be herein-after fully described and more particularly pointed out in the appended claim.

My invention will be more readily understood by reference to the accompanying drawings, forming a part of this specification, and in which—

35 Figure 1 is a perspective view of my improved rack in its preferred form, Fig. 2 is a vertical transverse section thereof, and Fig. 3 is a top plan view of a modified form of rack.

40 The preferred form of my invention as illustrated in the accompanying drawings comprises a backing plate 1 which is provided in its upper edge with key-hole perforations 2 engaging hooks on a wall or door, not shown. The lower edge of the backing plate 1 is provided with an upwardly extending longitudinal flange 3. Arranged in front of the backing plate 1 and extending longitudinally is a U-shaped loop 4 between which and the backing plate shoes

45 are placed as indicated in Fig. 1. In order to prevent dripping from wet shoes falling to the floor, a trough 5 is provided and detachably secured to the backing plate 1. 50 The securing means for the trough 5 comprising a downwardly extending longitudi-

dinal flange 6 formed thereon which engages the upwardly extending flange 3 of the backing plate 1. From this construction, it is apparent that the trough 5 may be readily 60 detached from the backing plate 1 and then emptied and cleansed if necessary whenever desired. The trough 5 is substantially semi-circular in cross section and formed of sheet metal, as is also the backing plate 1. It will 65 be observed that the flanges 3 and 6 are formed integral with the backing plate 1 and the trough 5 respectively, as clearly illustrated in Fig. 2.

In the modified form of my invention, a 70 series of loops 7 are substituted for the single loop 4 of the preferred form, said loops 7 being secured to the backing plate 1 by means of rivets 8. Each loop 7 is designed to receive and hold a single pair of rubbers, 75 hence the several members of a family may each be assigned a loop for their individual use. An advantage of the individual loop construction over the single loop construction is that the rubbers are held more se- 80 curely and in an orderly position.

It is apparent that the flange 3 which is arranged in front of the rear wall of the trough 5 will obviate any leakage of water, 85 since the latter drops directly from the shoes to the bottom of the trough.

In the operation of removing the trough for emptying the same, first an upward and then a downward movement of the trough is necessary for uncoupling the flange sec- 90 tions.

A shoe rack of the construction set forth is neat of appearance and highly efficient for the purpose for which it is designed.

While I have illustrated and described my 95 invention, this is capable of variation and modification without departing from the spirit of the invention. I, therefore, do not wish to be limited to the precise details of construction as set forth, but desire to avail myself of such variations and modifications as come within the scope of the appended 100 claim.

Having described my invention what I 105 claim as new and desire to secure by Letters Patent is:—

In a shoe rack, a rectangular backing plate having its lower edge turned back- 110 wardly and upwardly forming a flange, means for supporting said backing plate, shoe retaining means provided in front of said backing plate, and a suspended trough

substantially co-extensive with the length of said backing plate and having its rear side extended upwardly and then bent forwardly and downwardly forming a downwardly turned flange for engaging said upwardly turned flange, substantially as described.

In testimony whereof I have signed my name to this specification in the presence of two subscribing witnesses.

ANNA M. SUBBERG.
